UNITED STATES PATENT OFFICE.

RICHARD PEALE, OF ST. BENEDICT, PENNSYLVANIA, ASSIGNOR TO REMBRANDT PEALE, OF ST. BENEDICT, PENNSYLVANIA.

MINING MACHINE.

Application filed March 24, 1921. Serial No. 454,987.

To all whom it may concern:

Be it known that I, RICHARD PEALE, a citizen of the United States, residing in St. Benedict, in the county of Cambria and State of Pennsylvania, have made certain new and useful Improvements in Mining Machines, of which the following is a specification.

The invention relates to mining machines, and more especially to such machines for cutting a kerf about a horizontally extending core of coal and also to mechanism for conveying away the coal which drops from or is otherwise dislodged from the core in such a machine or any other suitable connection.

The objects and advantages of the invention will be set forth in part hereinafter and in part will be obvious herefrom, or may be learned by practice with the invention.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a longitudinal vertical section through a machine embodying the invention, taken on line 1—1 of Fig. 3;

Fig. 2 is a full end elevation, looking at Fig. 1 from the left or at Fig. 3 from the bottom;

Fig. 3 is a top plan corresponding to Fig. 2, but showing part of the machine in horizontal section on line 3—3 of Fig. 2;

Fig. 4 is a greatly enlarged, detached fragmentary detail, in horizontal section, of one of the reversing mechanisms for the conveyors, which is also shown in its connection in the machine at the central, left-hand part of Fig. 3;

Fig. 5 is a similar view to Fig. 4, showing the other driving and reversing gear for the other conveyor mechanism, which is shown in place in the machine at the lower central part of Fig. 3;

Fig. 6 is a detached, fragmentary detail, with parts in elevation and parts in verti-

cal section, of the conveyor blade and associated parts during the conveying stroke or travel;

Fig. 7 is a view similar to Fig. 6, but showing the conveyor blade returning on the idle stroke or travel;

Fig. 8 is a fragmentary, detached detail, taken in section substantially on the line 8—8 of Fig. 3, and showing the conveyor or pusher blades and certain of the cooperating parts;

Fig. 9 is a greatly enlarged, fragmentary vertical section, taken on the line 9—9 of Fig. 3, and showing the pusher blade at the end of its idle stroke and ready to begin the conveying stroke;

Fig. 10 is a similar view to Fig. 9, but showing the pusher blade in vertical position at the beginning of the conveying stroke;

Fig. 11 is a view similar to Fig. 9, but showing the means for raising the pusher blade to standing position mounted on the blade itself;

Fig. 12 is a similar view, but showing the pusher or conveyor blade in elevation in the position shown in dotted line in Fig. 11;

Fig. 13 is a diagrammatic elevation of the machine, showing the conveyor in relation to a pile of dislodged coal during the conveying stroke;

Fig. 14 is a similar view to Fig. 13, but showing the conveying mechanism returning on the idle stroke; and

Fig. 15 is a detached detail of a hand-operated reverse for the conveyor.

Fig. 16 is a section taken on the line 16—16 of Fig. 3.

The invention, as embodied, is directed to a mining machine adapted to cut a horizontally extending core out of the solid mine wall by cutting primarily a bottom kerf and a vertical and horizontal cooperating kerf, separating the core except at the back. The coal of most seams when so treated will fall of its own weight along the faces or natural planes of cleavage of the coal.

The invention provides primarily in cooperation means in such a machine adapted to cut very narrow kerfs and conveying means within the machine frame of such compact structure as to be adapted to enter such a narrow kerf and to quickly and effi-

ciently convey away the dislodged coal. Such a construction makes possible a machine of relatively exceedingly light construction, and of relatively very great efficiency, due largely to the reduction in the amount of work required in cutting the relatively thin kerfs.

More in detail, there is provided a thin, flat horizontal frame, preferably rectangular, with a cutter chain running about the exterior vertical face thereof to cut a bottom kerf; and within the frame are also means for cutting a cooperating kerf, which extends upwardly from and returns to the bottom kerf, this second kerf cutting means entering the bottom kerf as it is cut; and likewise within the frame is a conveyor which has one or more blades adapted to lie down when the machine is making the bottom kerf, and thereby to enter the kerf, and later to stand up to remove the dislodged coal after the kerfs are cut and the coal has dropped down into the machine.

Referring now in detail to the embodiment of the invention illustrated by way of example in the accompanying drawings, the exemplary mining machine so shown is the same or similar, in its general features at least, to the machine shown and described in my co-pending application S. N. 391,103, filed on June 23, 1920, so far as concerns the core cutting mechanism proper. In connection therewith, a new form of conveying mechanism is shown, which is of very strong and simple construction, but principally is of such compact structure as to permit a lightening of the whole machine and especially to allow the cutting of much narrower kerfs, especially the horizontal bottom kerf, than would be otherwise possible. This results from the fact that in this machine the conveyor enters the kerf as the kerf is cut and the kerf must be of sufficient height to admit the conveyor mechanism. With a conveyor of very compact construction, that is, one which is thin or occupies but a very small height within the machine frame when in the idle position (which position is occupied during the cutting of the bottom kerf while the conveyor is entering the kerf within the machine frame) permits of a correspondingly low or thin kerf being cut.

Other features and advantages of the invention will be set forth in connection with the different groups of mechanism as they are sequentially taken up, it being understood that both the foregoing and following descriptions are explanatory and not restrictive of the invention.

The embodied form of bottom kerf cutting means comprises a low, flat, horizontal frame 1, preferably of rectangular construction, with rounded corners, as shown in Fig. 3. On its exterior vertical face the frame 1

is provided with a horizontally disposed guideway 2, within which guideway runs a cutter chain 3 having teeth 4, the cutter chain and teeth being preferably of usual construction. Beneath the frame 1 is any suitable construction to provide for supporting the machine as it slides along the mine bottom, and to allow for the maintenance of the kerf and the entry of the machine as the cutter teeth wear away. For this purpose the frame 1 on its bottom is provided with skid rails 5, which may be of any suitable or convenient form.

The drive for the cutter chain may be of any suitable or convenient form, so far as concerns the main features of the present invention, and as shown are substantially the same as those in my said copending application S. N. 391,103. This drive comprises a motor 10 (Figs. 1 and 2), located at or adjacent to one of the rear corners of the frame 1 and having a beveled gear 11 fixed upon the motor shaft. The bevel gear 11 (Figs. 1, 2, and 3) meshes at one side 80 with a bevel gear 12, and at the other side 85 with a bevel gear 13, both of which gears are mounted loosely on a shaft 14. Shaft 14 is journaled in bearings 15 and 16, carried upon the machine frame.

Fixed to the bevel gear 12 to rotate therewith is a spur gear 18, and fixed to the bevel gear 13 to rotate therewith is a spur gear 19. Gear wheel 18 meshes with a gear wheel 20, and gear wheel 19 meshes with a gear wheel 21, and gear wheels 20 and 21 are mounted loosely upon a shaft 22. Shaft 22 is journaled in bearings 23 and 24 supported on the machine frame, and shown as having a common support with the journals 105 15 and 16 for the shaft 14.

On shaft 22 between gear wheel 20 and gear wheel 21 is a clutch member 25, mounted to rotate with shaft 22 but being slidable therewith. Fixed on gear wheel 20 is a clutch jaw 26, and fixed on gear wheel 21 is a clutch jaw 27. Clutch member 25 is slidable into engagement alternatively with clutch jaw 26 or 27, thereby driving shaft 22 in either one direction or the other, as may be desired, from the motor 10, through the train of gearing just described. Fixed on shaft 22 is a bevel gear wheel 30, which meshes with a crown bevel gear ring 31, fixed on a cutter chain driving wheel 32, the shaft 33 of which is suitably journaled in the machine frame. Wheel 32 has teeth 34, which mesh with recesses 35 in the cutter chain 3, thereby driving the chain in either direction as desired.

The cooperating kerf cutting means, which complete the cut around the horizontally extending core, comprises a traveling and rotating cutter bar, which is nested within the frame 1, longitudinally thereof, and along one of the side reaches of the

frame, as shown in Fig. 3. The cutter bar thus passes into the lower kerf as it is cut, and after the lower kerf is cut, the cutter bar is rotated and traveled, first vertically upwardly through the coal, then horizontally across, at or near the top of the seam, and then downwardly toward the farther end or side of the bottom kerf, to complete the cut about the horizontally extending core of coal to dislodge it and cause it to fall down into the machine upon the conveyor. The mechanism for effecting this is substantially the same or substantially similar to that shown in my said copending application S. N. 391,103. The cutter bar 45 (Figs. 1, 2 and 3) is fastened upon a shaft 46, which shaft has bearing blocks 47 and 48, adapted to run in double guideways 49 and 50, having vertical side reaches and a horizontal top reach (as best shown in Fig. 2), with connecting rounding corners, the blocks being shaped to run past the corners. Suitable bracing 52 may be employed as part of the guideway construction, and a central support 53 may also be used.

Means are provided for traveling the blocks 47 and 48 along their respective guideways to press the cutter bar 45 to the work and to make the cooperating kerf in the manner already described. Connected to the block 48 at each side thereof, and by its two ends, is a cable 56, which runs within the guideway 50. The cable 56 runs also over suitable guiding sheaves or pulleys 57 located at suitable points in the machine.

Cable 56 simultaneously winds on and off a drum 58, thereby traveling the cutter bar in either direction along its guideway, dependent upon the direction of rotation of the drum 58. Drum 58 is mounted loosely on a shaft 60, which shaft is journaled at 61 and 62 on the machine frame. One head of the drum 58 is formed as a cone clutch 63, and a cooperating cone clutching member 64 is keyed to shaft 60 to rotate therewith but slidable along the shaft into and out of clutching engagement with the drum.

Suitable actuating means for the clutch 64 are provided, which may be manual, but are omitted from the drawing for the sake of clearness. Fixed on shaft 60 is a worm wheel 65, with which meshes a worm 66, which is fixed on a shaft 67, the shaft being vertically disposed and journaled in a bearing 68 on the machine frame. Fixed also on shaft 67 is a spiral gear wheel 70. Meshing with the spiral gear 70 is a spiral gear 71, fixed on shaft 14.

Mounted on shaft 14 are two clutches or clutch members 72 and 73, rotatable with the shaft but movable therealong to pass alternatively into clutching engagement with the gear wheels 18 and 19, respectively. These clutches are likewise operated by suitable means, such as the usual hand levers,

which are omitted from the drawings for the sake of clearness. By means of these clutches, shaft 14 may be rotated in either direction and therewith the drum 58, thereby traveling the rotating cutter bar 45, to cut its kerf as described and thereafter to return to its nest within the frame 1.

Suitable means for rapidly rotating the cutter bar 45 are provided, and these may be the same or similar to those shown and described in my copending application S. N. 391,103, filed June 23, 1920.

As shown herein (Figs. 1 and 3), a gear wheel 85 is fixed to the other end of the shaft of motor 10 from the driving connections already described, and meshing therewith is a gear wheel 86, fixed on a shaft 87, which shaft is journaled at 88 and 289 on the machine frame. Fixed on shaft 87 are two sprocket wheels 89 and 90, and running thereover, respectively, are sprocket chains 91 and 92, the sprocket chains running also over sprocket wheels 93 and 94. These sprocket wheels are fixed on a shaft 95, which is journaled at 96 and 97 in the machine frame.

Fixed on shaft 95 is a sprocket wheel 98, over which runs a sprocket chain 99 (Figs. 1 and 3) running in the lower part of and along guideway 50. Sprocket chain 99 meshes with a sprocket wheel 100, which is fixed on shaft 46 of the cutter bar. In like manner, a sprocket wheel 101 is fixed on shaft 95, and a sprocket chain 102 runs about this wheel and upon and along the bottom channel of the guideway 49. Sprocket chain 102 meshes with a sprocket wheel 103 fixed on the shaft 46. The sprocket chains are arranged to run in the opposite directions to the cutter bar 45 during its cutting travel, and thereby rapidly rotate the cutter bar as it advances through the coal. As shown clearly in Fig. 16, the lower reaches of these chains 99 and 102 pass beneath the conveyor 114.

Referring now in detail to the embodied form of conveyor mechanism (shown in practically all the figures), a floor 114 extends from just within the front reach of the frame 1 horizontally, or substantially horizontally, backwardly along the machine, past the driving mechanism for the machine, and preferably for some distance to the rear of the back reach of the frame 1, as shown in Figs. 1 and 3. This enables the conveyor to discharge the coal clear of the back reach of the frame, or to connect with another conveyor without interference with the cutter chain.

The particular form of conveyor shown herein comprises a single conveyor or pusher blade 115 extending across, or nearly across, the entire width of the floor 114, and traveling substantially the entire length of floor 114. At each side thereof, the blade

15 has pivotal connections 116 and 117, respectively, with sprocket chains 118 and 119. The sprocket chain 118 at its inner end runs over an idler sprocket wheel 120, and at its outer end it runs over an idler sprocket wheel 121, the chain 118 returning beneath the floor 114 to the inner or front end of the machine and to the idler 120. In like manner, sprocket chain 119, at the front or inner end of the machine runs over an idler sprocket wheel 123 and at the rear or outer end of the machine, it runs over an idler sprocket wheel 124, this chain likewise returning beneath the floor 114. The floor 114 is spaced up above the bottom 125 of the machine frame just sufficiently to give passage way for the sprocket chains 118 and 119, and the bottom 125 may be solid or apertured as desired.

20 In the present embodiment, a single pusher blade 115 is preferably employed, traveling as stated substantially the entire distance from the inner or front end of the machine to the rear or outer end of the machine.

25 Means are provided, however, for varying the extent and locus of the travel of the pusher blade so that it will always be clear of any projecting portion of the core which has not been dislodged or disintegrated and fallen down in position for conveyance. The blade 115, in view of its lying down during the cutting of the bottom kerf, in its standing position may be higher than the frame 1, thus giving it greater conveying efficiency.

30 To permit the blade to lie down on its idle inward trip beneath the coal and to hold it upright or standing in its return trip, there are provided (see especially Figs. 6 to 8) on each of the chains 118 and 119 arms 127 pivoted respectively to the chains 128. These arms are provided, respectively, with slots 129 into which slots project corresponding pins 130 at each end of blade 114. The operation of this mechanism will be clear from Figs. 6 and 7 without further description.

By the mechanism just described, and as shown in detail in Figs. 6 to 12 the compactness and the small height or thinness 50 of the conveyor mechanism, when in idle position will be clearly understood, as the height is little more than that of the two superposed reaches of the chains 118 and 119, except at the inner end. The idler sprockets 120 and 123 may, however, be of very small diameter, and this permits the frame 1 to be of as thin or low structure as is compatible with necessary strength and 55 rigidity, thereby requiring but a very thin bottom kerf to be cut.

Suitable means may be employed for bringing the pusher blade 115 to standing position at the inner end of its trip, and for this purpose there is shown in Figs. 9 and 65 10 one or more hooks 136, which are pivoted

to the frame at 137, their ends being adapted to take over the top end of the pusher blade 115, thereby to bring it, as it starts on the conveying stroke, from the lying down position of Fig. 9 to the upstanding position of Fig. 10.

Another form of means for raising the blade is shown in Figs. 11 and 12, wherein a plurality of upwardly curved arms 138 are shown projecting from the top of the blade 115, which arms are adapted to engage with the coal and to bring the blade 114 to standing position. This device, it will be seen, will operate to bring the blade to its upstanding position, irrespective of the place of point at which the return or conveying stroke begins.

Suitable guiding or idler rollers may also be provided, such as a roller 140, adjacent to each of the idler sprockets 120 and 123, and rollers or sprocket wheels 142 and 143 may be arranged along the length of the chains 118 and 119. In Fig. 1 the floor 114 is shown upwardly inclined in its rear portion to pass over the back reach of the frame 1, the rollers or sprocket wheels 142 and 143 being located to keep the sprocket chains down on the floor 114.

Suitable driving means are provided for the main conveyor (Figs. 3 and 5), and as embodied, a gear wheel 150 is fixed on shaft 27, and meshing therewith is a pinion 151, which is fixed on a shaft 152, journaled at 153, 154 and 155 in the machine frame. This shaft is provided with a friction spring clutch 156. Fixed on shaft 152 are two gear wheels 157 and 158. Gear wheel 157 meshes with a gear wheel 159, which wheel is loose on a shaft 160, the shaft being journaled in bearings 161, 162 and 163 on the machine frame.

Gear wheel 158 meshes with an idler gear wheel 165, journaled on a stub shaft 166. Idler 165 meshes with a gear wheel 167 also mounted loosely on shaft 160. The idler serves to rotate gear wheel 167 in the opposite direction from gear wheel 159. A clutch member 170 is mounted on shaft 160 to rotate therewith, but is slidable therealong to pass alternatively into engagement 115 with a clutch member 171 on gear wheel 159 or with a clutch member 172 on gear wheel 167.

Means are provided (Figs. 3 and 5) for automatically operating clutch 170 to reverse the travel of the conveyor, and as embodied, an arm 175 has a pin engaging in an annular groove 176 in the clutch 170. Arm 175 is loosely mounted on a shaft 177. Mounted also on shaft 177 is a bell-crank 125 lever 178, one arm thereof having lugs 179 and 180 projecting upwardly on either side of the arm 175. The other arm of the bell-crank lever 178 is in the path of two tripping lugs 182 and 183, fastened at suit- 130

able points on the conveyor chain 118. Bell crank lever 178 is provided with a spring 184, adapted in a well-known manner to throw and to hold the lever on either side 5 of its center to prevent clutch 170 stopping in neutral position and thus stopping the conveyor.

Thus, when one of the lugs 182 or 183 engages the bell-crank lever 178, as soon as 10 the lever passes the dead center, the spring 184 snaps it to the other end of its throw, and the clutch 170 is thrown positively into engagement with the clutch member 171 or 172, as the case may be, and the possibility 15 of its stopping on neutral position is avoided. It will be seen that by adjustment or positioning of the lugs 182 or 183 along the chain 118 that the distance of travel of the conveyor blade can be varied as desired. 20 Fixed on shaft 160 are sprocket wheels 186 and 187 meshing, respectively, with the chains 118 and 119 beneath the floor 114, to drive the chain and thereby the conveyor mechanism.

25 In accordance with one feature of the invention, a short cross conveyor is provided (Figs. 3 and 4) adapted to transfer or convey the dislodged coal crosswise into the path of the main conveyor just described. 30 The general construction may be the same as that already described, and the parts are shown in Fig. 3. A conveyor blade 190 is shown connected to endless sprocket chains 191 and 192 in the manner already described 35 for the blade 115. These sprocket chains run, respectively, over idle sprocket wheels 193 and 194 and also, respectively, over driving sprocket wheels 195 and 196. These latter wheels are fixed on a shaft 197, journaled in the machine frame at suitable points 40 and also in the bearing 198. Shaft 197 is provided preferably with a spring friction clutch 199.

45 Fixed on shaft 197 is a bevel gear 200, meshing with a bevel gear 201, which is fixed on a shaft 202, the shaft being journaled at 203, 204 and 205 on the machine frame. Mounted loosely on shaft 197 (Figs. 3 and 4) are bevel gear wheels 206 and 207, 50 provided respectively with clutch members 208 and 209, integral therewith. Between them is a cooperating clutch member 210, rotatable with shaft 197, but slideable therealong. Meshing with bevel gears 203 and 55 207 is a bevel gear 211, which is fixed on shaft 87, the shaft being driven from the motor 10, as already described.

60 The reversing means for this conveyor, as embodied, comprises a lever 212, pivoted at 213, and having a pin projecting into an annular groove 214 formed in the clutch 210. Pivots connected to the other end of lever 212 is a link 216, the other end thereof being pivoted at 217 to a bell-crank 65 lever 218, which lever is pivoted at 219 upon

the machine frame. Pivots connected to the other end of lever 218 is a link 220, the other end thereof being pivoted at 221 to a bell-crank lever 222. Bell-crank lever 222 is pivots supported upon the machine 70 frame at 223.

Also pivots supported at 223 is an arm 224, having fixed thereto lugs 225 and 226, projecting up at either side of the arm 227 of bell-crank lever 222. Pivots connected to arm 227 is a rod 229, extending along sprocket chain 192, and having lugs 230 and 231 in the path of a stop 232, fixed in adjustable position upon the sprocket chain 192. It will be clear that two stops 232 may be employed if desired. A spring 233 is provided for throwing the lever 234 over its center to prevent the clutch 210 stopping in neutral position as already described. 85

Suitable baffle plates may be provided at all necessary or desirable points to prevent interference of the moving material with the mechanism. In Fig. 8 a baffle plate 234 is shown, which lifts the coal fed in by 90 the cross conveyor into the path of the main conveyor over the sprocket chain 118. This plate 234 is not shown in Figure 1 as it is desired to show the location of the chain 118. A similar baffle plate 235 is shown at the end 95 of the main conveyor, and a housing 236 is shown over the front end of the main conveyor. These baffles 235 are merely vertically disposed plates of proper size and shape to direct the coal in a path over the floor of the conveyors and to keep the coal from pushing against the rollers or other moving parts. 100

In Figs. 13 and 14 there is shown in a diagrammatic manner the general action of 105 the conveyor in conveying away the dislodged coal.

The machine will be provided with means for pressing it to the work, which may be of the winding cable type, and need not be 110 described in detail. Such mechanism may be the same or similar to that shown in my copending application Ser. No. 454,986. Only a portion of this mechanism is therefore shown in this case. Meshing with gear wheel 20 is a gear wheel 240, which is fixed on a shaft 241, having suitable bearings 242 in the machine frame. Fixed on shaft 241 are drums 243, upon which are wound the cables which press the machine to the 115 work. 120

In Fig. 15 a manually operated reversing device is shown for the conveyor. As shown, a longitudinally reciprocable handle 250, is loosely connected to arm 178 (which arm is 125 shown also in Figs. 1 and 5). By operating this handle at will, the blade or blades 115 may be reciprocated along only a portion of the full path of travel. For instance, it could be run from the front only part way 130

under a pile of dislodged coal, just sufficiently to get a full load, and then be drawn outwardly, thereby avoiding waste of power in pulling the blade and its load an unnecessary distance, which might be the case if the blade necessarily always traveled the entire length of the machine. This means may be employed in addition to or alternatively with the automatically operating reversing means, which is also settable to vary the distance of travel of the blade. The blade 115 is not necessarily limited to the height of the machine frame, but may be made higher if desired.

15. The invention in its broader aspects is not limited to the specific mechanisms shown and described but departures may be made therefrom within the scope of the accompanying claims without departing from the principles of the invention and without sacrificing its chief advantages.

What I claim is:—

1. A mining machine including in combination means for cutting a bottom horizontal kerf, a rotatable cutter bar nested within said kerf cutting means, means for moving the rotating cutter bar to cut a co-operating kerf, and a conveyor extending from the front to the rear of the machine and having a pusher blade nested within said bottom kerf cutting means.

2. A mining machine including in combination means for cutting a bottom horizontal kerf, a rotatable cutter bar nested within said kerf cutting means, means for moving the rotating cutter bar to cut a co-operating kerf, and a conveyor extending from the front to the rear of the machine and having a pusher blade adapted to lie flat and to stand up within said bottom kerf cutting means when traveling, respectively, in the idle and conveying directions.

3. A mining machine including in combination a low, flat horizontal frame, a cutter chain running about the exterior thereof to cut a bottom kerf, a rotatable cutter bar nested within the frame, means for moving the rotating cutter bar to cut a co-operating kerf, and a conveyor extending from the front to the rear of the frame and having a pusher blade nested within the frame.

4. A mining machine including in combination a low, flat horizontal frame, a cutter chain running about the exterior thereof to cut a bottom kerf, a rotatable cutter bar nested within the frame, means for moving the rotating cutter bar to cut a co-operating kerf, and a conveyor extending from the front to the rear of the frame and having a pusher blade adapted to lie flat and to stand up within the frame when traveling, respectively, in the idle and conveying directions.

5. A mining machine including in combination a low, flat horizontal frame, a

cutter chain running about the exterior thereof to cut a bottom kerf, a rotatable cutter bar nested just within and alongside one of the sides of the frame, means for moving the rotating cutter bar to cut a co-operating kerf, and a conveyor extending from the front to the back of the frame and located within the cutter chain and having a pusher blade adapted to lie down and to stand up within the frame when traveling, respectively, in the idle and conveying directions.

6. A mining machine including in combination means for cutting a bottom horizontal kerf, a rotatable cutter bar nested within said kerf cutting means, means for moving the rotating cutter bar to cut a co-operating kerf, and a conveyor extending from the front to the rear of the machine and having a pusher blade adapted to lie flat and to stand up within said bottom kerf cutting means when traveling, respectively, in the idle and conveying directions, and means for imparting reciprocating travel to the pusher blade.

7. A mining machine including in combination a low, flat horizontal frame, a cutter chain running about the exterior thereof to cut a bottom kerf, a rotatable cutter bar nested within the frame, means for moving the rotating cutter bar to cut a co-operating kerf, and a conveyor extending from the front to the rear of the frame and having a pusher blade adapted to lie flat and to stand up within the frame when traveling, respectively, in the idle and conveying directions, and means for imparting reciprocating travel to the pusher blade.

8. A mining machine including in combination a low, flat horizontal frame, a cutter chain running about the exterior thereof to cut a bottom kerf, a rotatable cutter bar nested just within and alongside one of the sides of the frame, means for moving the rotating cutter bar to cut a co-operating kerf, and a conveyor extending from the front to the back of the frame and located within the cutter chain and having a pusher blade adapted to lie down and to stand up within the frame when traveling, respectively, in the idle and conveying directions, and means for imparting reciprocating travel to the pusher blade.

9. A mining machine including in combination a low, flat horizontal frame, a cutter chain running about the exterior thereof to cut a bottom kerf, a rotatable cutter bar nested just within and alongside one of the sides of the frame, means for moving the rotating cutter bar to cut a co-operating kerf, and a conveyor extending from the front to the back of the frame and located within the cutter chain and having a pusher blade adapted to lie down and to stand up within the frame when

traveling, respectively, in the idle and conveying directions, the pusher blade projecting above said low, flat frame when standing in conveying position.

5 10. A mining machine including in combination a low, flat horizontal frame, a cutter chain running about the exterior thereof to cut a bottom kerf, a rotatable cutter bar nested within the frame, means 70 for moving the rotating cutter bar to cut a cooperating kerf, and a conveyor extending from the front to the rear of the frame and having a pusher blade adapted to lie flat and to stand up within the frame when 75 traveling, respectively, in the idle and conveying directions, the pusher blade projecting above said low, flat frame when standing in conveying position.

11. A mining machine including in combination means for cutting a bottom horizontal kerf, a rotatable cutter bar nested within said kerf cutting means, means for moving the rotating cutter bar to cut a cooperating kerf, and a conveyor extending 80 from the front to the rear of the machine and having a pusher blade adapted to lie flat and to stand up within said bottom kerf cutting means when traveling, respectively, in the idle and conveying directions, 85 20 the pusher blade projecting above said bottom kerf cutting means when standing in conveying position.

12. A mining machine including in combination means for cutting a bottom horizontal kerf, a rotatable cutter bar nested within said kerf cutting means, means for moving the rotating cutter bar to cut a cooperating kerf, and a conveyor extending 90 from the front to the rear of the machine 95 and having a pusher blade nesting within said bottom kerf cutting means, a motor mounted on and at the rear of the machine and connections therefrom for driving the bottom kerf cutter, the rotary cutter bar and the conveyor.

13. A mining machine including in combination a low, flat horizontal frame, a cutter chain running about the exterior thereof to cut a bottom kerf, a rotatable cutter bar nested within the frame, means for moving the rotating cutter bar to cut a cooperating kerf, and a conveyor extending 100 from the front to the rear of the frame and having a pusher blade nested within the frame, a motor mounted on and at the rear of the machine and connections therefrom for driving the bottom kerf cutter, the rotary cutter bar and the conveyor.

14. A mining machine including in combination means for cutting a bottom horizontal kerf, a rotatable cutter bar nested within said kerf cutting means, means for moving the rotating cutter bar to cut a cooperating kerf, and a conveyor extending 105 from the front to the rear of the machine

and having a pusher blade adapted to lie flat and to stand up within said bottom kerf cutting means when traveling, respectively, in the idle and conveying directions, and means for imparting reciprocating travel to the pusher blade, a motor mounted on and at the rear of the machine and connections therefrom for driving the bottom kerf cutter, the rotary cutter bar and the reciprocating pusher blade traveling means.

15. A mining machine including in combination a low, flat horizontal frame, a cutter chain running about the exterior thereof to cut a bottom kerf, a rotatable cutter bar nested within the frame, means for moving the rotating cutter bar to cut a cooperating kerf, and a conveyor extending 110 from the front to the rear of the frame and having a pusher blade adapted to lie flat and to stand up within the frame when traveling, respectively, in the idle and conveying directions, and means for imparting reciprocating travel to the pusher blade, a motor mounted on and at the rear of the machine and connections therefrom for driving the bottom kerf cutter, the rotary cutter bar and the reciprocating pusher blade traveling means.

16. A mining machine including in combination a low, flat horizontal frame, a cutter chain running about the exterior thereof to cut a bottom kerf, a rotatable cutter bar nested just within and alongside one of the sides of the frame, means for moving the rotating cutter bar to cut a cooperating kerf, and a conveyor extending 115 from the front to the back of the frame and located within the cutter chain and having a pusher blade adapted to lie down and to stand up within the frame when traveling, respectively, in the idle and conveying directions, and means for imparting reciprocating travel to the pusher blade, a motor mounted on and at the rear of the machine and connections therefrom for driving the bottom kerf cutter, the rotary cutter bar and the reciprocating pusher blade traveling means.

17. A mining machine including in combination, a low, flat horizontal frame adapted to slide upon the ground and to enter a kerf, a cutter chain running about the exterior of the frame to cut a bottom kerf of sufficient size to receive the frame, conveying means within the frame and extending from the front of the frame longitudinally thereof to the rear and extending outwardly just above and beyond the back of the frame, and a motor mounted on said frame to drive said cutter chain and said conveying means.

18. A mining machine including in combination, a low, flat horizontal frame adapted to slide upon the ground and to

enter the kerf, a cutter chain running about the exterior of the frame to cut a bottom kerf of a size to receive the frame, and conveying means within the frame comprising a floor extending from the front of the frame rearwardly just over and beyond the back of the frame and the cutter chain, and means for pushing dislodged coal along said floor, and a motor mounted on said frame to drive said cutter chain and said conveying means.

19. A mining machine including in combination, a low, flat horizontal frame adapted to slide along the ground and to enter a kerf, a cutter chain running about the exterior of the frame to cut a bottom kerf adapted to receive the frame, conveying means within the frame and comprising a floor extending from the front of the frame rearwardly, just over and beyond the back of the frame and the cutter chain, means including a traveling pusher blade for pushing dislodged coal along said floor, and a motor mounted on said frame to drive said cutter chain and said conveying means.

20. A mining machine including in combination, a low, flat horizontal frame adapted to slide upon the ground and to enter a kerf, a cutter chain running about the exterior of the frame to cut a bottom kerf to receive the frame, conveying means within the frame and comprising a floor extending from the front of the frame rearwardly just over and beyond the back of the frame and the cutter chain, and means including a reciprocable pusher blade traveling nearly the entire length of said floor for pushing dislodged coal along said floor.

40 21. A mining machine including in combination a low, flat horizontal frame, a cutter chain running about the exterior of the frame to cut a bottom kerf, and conveying means within the frame and comprising a floor extending from the front of the frame rearwardly just over and beyond the back of the frame and the cutter chain and means including a traveling reciprocable pusher blade for pushing dislodged coal along said floor.

22. A mining machine including in combination a low, flat horizontal frame, a cutter chain running about the exterior of the frame to cut a bottom kerf, and conveying means within the frame and comprising a floor extending from the front of the frame rearwardly just over and beyond the back of the frame and the cutter chain and means including a pusher blade traveling reciprocably nearly the entire length of said floor for pushing dislodged coal along said floor.

60 23. A mining machine including in combination a low, flat horizontal frame, a cutter chain running about the exterior of the frame to cut a bottom kerf, and conveying

means within the frame and comprising a floor extending from the front of the frame rearwardly just over and beyond the back of the frame and the cutter chain and means including a traveling pusher blade adapted to lie down when traveling idly and to stand up for pushing dislodged coal along said floor.

24. A mining machine including in combination a low, flat horizontal frame, a cutter chain running about the exterior of the frame to cut a bottom kerf, and conveying means within the frame and comprising a floor extending from the front of the frame rearwardly just over and beyond the back of the frame and the cutter chain and means including a pusher blade traveling nearly the entire length of said floor adapted to lie down when traveling idly and to stand up for pushing dislodged coal along said floor.

25. A mining machine including in combination a low, flat horizontal frame, a cutter chain running about the exterior of the frame to cut a bottom kerf, and conveying means within the frame and comprising a floor extending from the front of the frame rearwardly just over and beyond the back of the frame and the cutter chain and means including a traveling reciprocable pusher blade adapted to lie down on its idle reciprocation and to stand up for pushing dislodged coal along said floor.

26. A mining machine including in combination a low, flat horizontal frame, a cutter chain running about the exterior of the frame to cut a bottom kerf, and conveying means within the frame and comprising a floor extending from the front of the frame rearwardly just over and beyond the back of the frame and the cutter chain and means including a pusher blade traveling reciprocably nearly the entire length of said floor and adapted to lie down on its idle reciprocation and to stand up for pushing dislodged coal along said floor.

27. A conveyor mechanism comprising a bottom supporting the material to be conveyed, a pusher blade, means for traveling it along the bottom, and means for varying the extent of its travel.

28. A conveyor mechanism comprising a bottom supporting the material to be conveyed, a pusher blade, means for traveling it to and fro along the bottom, and means for varying the extent of its travel.

29. A conveyor mechanism comprising a bottom supporting the material to be conveyed, a pusher blade, means for traveling it along the bottom, and manually operable means for varying the extent of its travel.

30. A conveyor mechanism comprising a bottom supporting the material to be conveyed, a pusher blade, means for traveling it to and fro along the bottom, and man-

ually operable means for varying the extent of its travel.

31. A conveyor mechanism comprising a bottom supporting the material to be conveyed, an upwardly projecting pusher blade, means for traveling it along the bottom, and means for varying the extent of its travel.

32. A conveyor mechanism comprising a bottom supporting the material to be conveyed, an upwardly projecting pusher blade, means for traveling it to and fro along the bottom, and means for varying the extent of its travel.

33. A conveyor mechanism comprising a bottom supporting the material to be conveyed, an upwardly projecting pusher blade, means for traveling it along the bottom, and manually operable means for varying the extent of its travel.

34. A conveyor mechanism comprising a bottom supporting the material to be conveyed, an upwardly projecting pusher blade, means for traveling it to and fro along the bottom, and manually operable means for varying the extent of its travel.

35. A conveyor mechanism comprising a bottom supporting the material to be conveyed, a rising and falling pusher blade, means for traveling it along the bottom, and means for varying the extent of its travel.

36. A conveyor mechanism comprising a bottom supporting the material to be conveyed, a rising and falling pusher blade, means for traveling it to and fro along the

bottom, and means for varying the extent of its travel.

37. A conveyor mechanism comprising a bottom supporting the material to be conveyed, a rising and falling pusher blade, means for traveling it along the bottom, and manually operable means for varying the extent of its travel.

38. A conveyor mechanism comprising a bottom supporting the material to be conveyed, a rising and falling pusher blade, means for traveling it to and fro along the bottom, and manually operable means for varying the extent of its travel.

39. A conveyor mechanism comprising a bottom supporting the material to be conveyed, an upwardly projecting, rising and falling pusher blade, means for traveling it along the bottom, and means for varying the extent of its travel.

40. A conveyor mechanism comprising a bottom supporting the material to be conveyed, an upwardly projecting, rising and falling pusher blade, means for traveling it to and fro along the bottom, and means for varying the extent of its travel.

41. A conveyor mechanism comprising a bottom supporting the material to be conveyed, an upwardly projecting, rising and falling pusher blade, means for traveling it to and fro along the bottom, and manually operable means for varying the extent of its travel.

In testimony whereof, I have signed my name to this specification.

RICHARD PEALE.
